UNITED STATES PATENT OFFICE

WILLIAM T. EISENHARDT, OF BALTIMORE, MARYLAND, ASSIGNOR TO WILLIAM J. EISENHARDT, OF BALTIMORE, MARYLAND

SUGAR DISPENSER

Application filed September 25, 1931. Serial No. 565,123.

This invention relates to improvements in sugar dispensers, and has for its object to provide a container for dispensing sugar or other similar products in measured, or predetermined, quantities.

A further object of my invention is to provide a dispensing tube that is simple in construction and which may be employed in a great many dispensers now in general use, whereby the contents may be dispensed in measured, or predetermined, quantities.

The invention consists of the novel construction and arrangement of parts and combination of parts hereinafter more fully set forth in the following specifications and pointed out in detail in the appended claims:

In the accompanying drawing:—

Figure 1 is an elevation of a container embodying my invention.

20 Figure 2 is a vertical longitudinal section of Figure 1, the dispensing tube being partly in section.

Figure 3 is a plan view of Figure 1.

25 Figure 4 is a detail top plan view of the dispensing tube and retaining spring.

Figure 5 is an inverted plan view of Figure 4.

Referring to the accompanying drawing, forming part of this specification, and in which like reference numerals designate like parts throughout the several views thereof, 1 designates a glass container having a neck 2 on its upper end provided with a central aperture 3. The lower end of the receptacle 1 is open and is screw-threaded on its outer surface at 4. A screw-threaded cap 5 is removably secured to the threaded end of the receptacle 1 to close the latter. Within the receptacle 1 is a removable hollow tube 6 adapted to fit up in the neck 2 in vertical alignment with the aperture 3. The said tube 6 is open at both ends and its lower end is provided with a flange 10. Secured to the lower flanged end of the tube 6 is a retaining spring 7 which has an aperture 8 in line with the opening through tube 6. The said spring 7 extends outwardly from opposite sides of the tube 6 and has its extremities 9 bent inwardly, as shown in Figure 2 of the drawing.

53 When the tube 6 is inserted in the receptacle

1 it is pushed up through the opening in the bottom thereof and will assume the position shown in Figure 2 of the drawing, with the upper end in line with the opening 3. The tube 6 is held in position by the action of the 55 spring 7 against the inner surface of the receptacle 1, and when the cap 5 is screwed on the lower end of the receptacle it will impinge against the extremities 9 of the spring 7 forcing them upwardly and the tension of 60 the spring 7 will hold the tube 6 securely in position in alignment with the opening 3. The flange 10 on the lower end of the tube 6 will hold a certain amount of sugar when the container is inverted and cause it to flow 65 through the tube 6. The tube 6 can be of any desired length and the amount of sugar to be dispensed will depend upon the space between the lower end of the tube 6 and the cap 5. Assuming the receptacle 1 is filled 70 with sugar, or other product to be dispensed, each time it is inverted the amount of sugar between the lower end of the tube and the cap 5 will flow through the said tube.

Having thus described my invention what 75 I claim is:—

1. A dispenser comprising a receptacle having an aperture in one end and its opposite end open, a closure for the open end of said receptacle, a dispensing tube within said receptacle having one end in alignment with said aperture and its opposite end provided with a flange and held a predetermined distance from the bottom of said receptacle, and a spring secured to the flanged end of said tube and having its outer ends impinging against the inner surface of said receptacle. 85

2. A dispenser comprising a receptacle having a central aperture in one end and its opposite end open, a closure for the open end of said receptacle, a dispensing tube within said receptacle having one end in alignment with said central aperture and its opposite end held a predetermined distance from the bottom of said receptacle and having a flange thereon, a spring secured to the flanged end of said tube and extending outwardly from opposite sides thereof and impinging against the inner surface of said receptacle to hold the tube in vertical alignment with said central aperture 95 100

and its extremities bent inwardly and downwardly and impinging against the bottom of said receptacle to hold the tube in proper relation to the bottom.

3. A dispensing tube comprising a hollow tube open at each end and one end having a flange projecting therefrom, and a spring extending from opposite sides of said flanged end of the tube and having its extremities bent inwardly and downwardly beyond the flanged end of the tube.

In testimony whereof I affix my signature.

WILLIAM T. EISENHARDT.
